UNITED STATES PATENT OFFICE.

OTTO U. JAHELKA, OF BALTIMORE, MARYLAND.

DESIGN FOR A HAIRPIN.

Application filed May 8, 1922. Serial No. 2,134. Term of patent 14 years.

To all whom it may concern:

Be it known that I, OTTO U. JAHELKA, a citizen of the United States, residing at Baltimore, State of Maryland, have invented a certain new, original, and ornamental Design for Hairpins, of which the following is a specification, reference being had to the accompanying drawings, forming part thereof.

The figure is an enlarged plan view of the hair pin.

I claim:

The ornamental design for a hair pin, as shown.

In testimony whereof I hereunto affix my signature.

OTTO U. JAHELKA.
